UNITED STATES PATENT OFFICE.

THOMAS H. BOTTOMLEY, OF CAPAC, MICHIGAN.

DOOR-HANGER.

SPECIFICATION forming part of Letters Patent No. 223,985, dated February 3, 1880.

Application filed August 9, 1879.

To all whom it may concern:

Be it known that I, THOMAS H. BOTTOMLEY, of Capac, in the county of St. Clair and State of Michigan, have invented an Improvement in Door-Hangers, of which the following is a specification.

The nature of my invention relates to certain new and useful improvements in that class of devices employed for suspending rolling gates or doors; and the invention consists in the details of construction of the various parts and their combinations, as more fully hereinafter set forth.

In the accompanying drawing, which forms a part of this specification, and represents my invention in perspective, A represents a hanger or standard provided with an overhanging bearing-wheel, B, which is designed to travel upon the top of the rail D, and thereby suspend the door or gate to which the standard is secured. This rail D is provided upon its under side with the groove E, to receive the guide-wheel C, which rotates upon a bearing projecting from the face of the standard, as shown, and prevents the door or gate from swinging out of line.

It will be seen that both the bearing-wheel and the guide-wheel are flat-faced sheaves, which are very cheap to construct and require no nice fit to be made with the rail. The upper part of the rail, upon which the bearing-wheel runs, is also flat, so that the friction is reduced to the minimum, the guide-wheel alone preventing the outward movement of the hanger and being most of the time itself wholly out of contact with the groove in which it moves.

What I claim as my invention is—

The combination, with the rail D, having flat top and groove E on its under side, of the flat sheave-hanger composed of plate A, flat bearing-wheel B, and flat guide-wheel C, both of said wheels revolving vertically on horizontal studs projecting from such plate, constructed and arranged substantially as described and shown.

THOS. H. BOTTOMLEY.
